INVENTOR=

Louis Gathmann.

for Mr. E. Dayton, Attorney.

UNITED STATES PATENT OFFICE.

LOUIS GATHMANN, OF CHICAGO, ILLINOIS.

BOLTING APPARATUS FOR FLOUR-MILLS.

SPECIFICATION forming part of Letters Patent No. 228,751, dated June 15, 1880.

Application filed February 25, 1880.

To all whom it may concern:

Be it known that I, LOUIS GATHMANN, of Chicago, State of Illinois, have invented certain new and useful Improvements in Bolting or Separating Apparatus for Flour-Mills; and I do hereby declare that the following is a full, clear, and exact description thereof, reference being had to the accompanying drawings, and to the letters of reference marked thereon, 10 which form a part of this specification.

This invention relates to bolting or separating apparatus for flouring-mills; and it consists in the combination hereinafter specified, with the screens or bolts of a purifier having 15 an air-blast, of a dust-collector arranged within the machine and in the air-passage thereof, so as to intercept the air-current after it has passed the screens, substantially as herein described.

20 In the drawings, Figures 1 and 2 are side elevations of a purifier containing both my improvements. Fig. 3 is a central vertical longitudinal section of the same. Fig. 4 is a transverse vertical section of the machine through 25 the line *y y* of Fig. 3. Fig. 5 is a detail view, showing part of the mechanism whereby the dust-cloth is actuated. Fig. 6 is a top view of one of the bolting-screens of the purifier, and Fig. 7 is an under-side view of the coarse netting and its frame by which the bolting-cloth 30 is cleaned.

The general features and construction of the purifier are not new, and being familiar to those skilled in the art need not be here particularly described.

35 A and B respectively represent the framework and inclosing sides of the machine. S is the vibrating shoe, carrying the screens and the various conveying-boards, and actuated 40 through the rod O from an eccentric on the shaft of the suction-fan F. The usual openings and passages are provided for the material to be operated upon and for the air.

The devices for clearing the meshes of the 45 bolts and screens will be first described.

In the drawings, *h h* represent the several screen-cloths, mounted in the usual manner on inclined frames *f* within the shoe S.

50 Within the opening of each of the screen-frames *f*, and beneath the bolting-cloth thereof, is placed the frame *f'*, shorter than said open-

ing in the direction of movement of the screen and clothed with coarse or open netting on its upper surface. The frames are intended to be lifted at brief intervals, so as to bring the netting into momentary contact with the under surface of the bolts *h*, for the purpose of clearing their meshes by a rubbing action of one upon the other. Provision is made for their support parallel with the bolting-cloths *h*, and, 55 say, half an inch therefrom, by the transverse bars *p p*. The screens being movable in their planes, it is desirable that the cleaners should be stationary in this direction; wherefore, the bars *p* are fixed to the sides B of the purifier, 60 and slots *s* are provided in the sides of the moving shoe for their passage.

Each cleaner is lifted by means of an arm, *m*, and in order to secure even bearing of the cleaner against the bolting-cloth, said arm *m* 70 bears upward against the middle of a central rail, *i*, of the cleaner-frame *f'*. This central rail is notched at *n* to receive the arm *m*, in order that the cleaner may be held horizontally stationary by said arm while in contact 75 with the reciprocating bolt *h*.

The arms for the several cleaners are pivoted to the rail I, fixed to the casing B, and pass through slots *s'* in the side of the shoe.

The arms *m* are also pivotally connected to 80 the movable vertical bar J. This bar is worked by the lever K and pulley L, the latter having the pin *u*, arranged to strike the lever K at each revolution, as clearly shown in Fig. 2. The cleaners, bearing on the long arms *m*, fall 85 by their own weight.

To insure more even pressure of the cleaners upon the bolts *h*, the rails *g* are secured to the bolt-frames above the bolting-cloth and in contact therewith, as shown in the several 90 Figs. 3, 4, and 6.

The arms *m* are preferably of wood, and formed, as indicated, to spring, and thus to press yieldingly upward against the cleaners, that the frictional contact of the latter with 95 the bolts may not be too severe.

The cleaner may, if desired, be given an independent movement parallel with the screens.

A special advantage of a cleaner of netting is found in the fact that it does not appreciably obstruct the passage of the air upward through the bolt or screen while the latter is 100

being acted upon thereby. The movement by which the cleaners are brought into contact with the bolts may be varied to give any required frequency or duration of contact. 5 Once a minute will ordinarily be sufficient to insure perfect action of the bolts, the actual contact of the cleaners with the bolts being very brief.

The devices for collecting the dust and impurities will be next described.

Between the shoe S and the fan F of a suction-purifier, or next beyond the screens in the direction of the air-current, is placed the dust-screen B, consisting of a loosely-woven sheet, 15 c, of flannel or other similar material drawn taut, and supported in the inclined position shown in Fig. 3 upon the frame E. This frame has the central rail, E', and fills the space between the walls of the chamber in which it is 20 placed. In the operation of the machine the air from the screens passes through this cloth and deposits its burden of dust and impurities thereon.

It is obvious that in the inclined position 25 of the dust-collecting cloth, as shown, a sudden and frequent jarring thereof will detach the dust thereon accumulated, and that the detached dust, after, perhaps, repeatedly being again drawn to the cloth at lower points, 30 will ultimately fall beyond the range of the air-current, and will settle in quiet mass at the bottom of the chamber, whence it may be removed by any suitable carrier or conveyer.

For the purpose of jarring the cloth to detach the impurities intercepted, a knocker is 35 provided, consisting of the lever R, pivoted to the marginal rail of the frame E, and arranged to strike the central rail, E', against which the cloth rests. This lever R is actuated to strike 40 the frame by a spring, P, applied as shown, or in any other suitable manner, and is lifted by means of the external cam-pulley, P', pivoted to engage the protruding end of the lever R by the cam c. The blow of the striker is thus 45 calculated to throw the impurities detached thereby against the air-current, so that in fact

they are allowed to fall a considerable distance before being again drawn by the constant current to the cloth.

For the purpose of distributing the jarring 50 effect more perfectly over the entire area of the cloth, as well as for the better support of the latter, a coarse netting of wire, w, is secured over the aperture of the frame E beneath the dust-cloth. This feature of the collector, however, is not of my invention.

Instead of a knocker arranged to strike the collector-frame E, the entire frame may be made movable and be directly vibrated through a projecting arm, R, rigidly secured thereto, 60 or otherwise, as may be found most effective or convenient; or a series of wings, each bearing a suitable cloth, may be arranged to rotate successively into and out of the current in such manner as that the passage of the latter shall always be intercepted by some one or more of them, and as they fall out of the current they may be struck in the manner described to dislodge the dust deposited thereon.

Having thus described my invention, I 70 claim—

1. An air-blast separator provided with a dust-arrester, arranged in a vertical, or nearly vertical, position, to intercept the horizontal air-current, and combined with mechanism for 75 detaching the dust, and with a space at its foot, outside the range of the current, to receive the dust, substantially as described.

2. The dust-arrester D, arranged within a purifier, to intercept the air-current in its passage from the screens, the lever R, the spring P, and the cam-pulley P', combined and operating substantially as and for the purposes described.

In testimony that I claim the foregoing as 85 my invention I affix my signature in presence of two witnesses.

LOUIS GATHMANN.
